UNITED STATES PATENT OFFICE.

HENRY R. WEBB, OF ST. LOUIS, MISSOURI.

SUSPENDER-BUCKLE.

No. 800,421.

Specification of Letters Patent.

Patented Sept. 26, 1905.

Application filed March 7, 1905. Serial No. 248,943.

To all whom it may concern:

Be it known that I, HENRY R. WEBB, a citizen of the United States, and a resident of the city of St. Louis, Missouri, have invented certain new and useful Improvements in Suspender-Buckles, of which the following is a specification containing a full, clear, and exact description, reference being had to the accompanying drawings, forming a part hereof.

10 My invention relates to that class of suspenders wherein the shoulder-straps are adjustable at their front ends.

15 The object of my invention is to provide suspenders with improved means whereby the front ends of the shoulder-straps may be shortened from time to time in order to compensate for undue stretching caused by wear.

20 The further object of my invention is to provide improved means for the purpose just mentioned whereby the front ends of the suspenders may be readily detached from time to time and the buckle be kept at substantially its original position.

25 Heretofore in suspenders of this class when the shoulder-straps have been shortened by adjusting the buckle farther up as the length of the straps was increased by a long-continued service the buckle was permanently secured to the shoulder-straps by stitching or 30 rivets and had to be moved so far upwardly that it rested upon the shoulder of the wearer and caused pain and injury in many cases. Such defect has been obviated by my improved construction.

35 In the drawings, Figure 1 is a side elevation of the front end of a shoulder-strap, showing the inner side thereof. Fig. 2 is an edge view of the same. Fig. 3 is a section on the line 3 3 of Fig. 4. Fig. 4 is an enlarged rear 40 elevation of an improved buckle made use of in carrying out my invention.

1 indicates the shoulder-strap, and 2 the buttonhole-straps.

45 In carrying out my invention I make use of the buckle 3, having the usual cross-bar 4 and strap-openings 5. Upon the inner surface of the said buckle 3 is fixed an additional cross-bar 6, carrying the downwardly-projecting prongs 7. The last-mentioned cross-bar 6 is 50 what I term the "prong-bar," although in reality said prong-bar is formed integral with

said cross-bar 4 and forms a part thereof. Said bar 6 is provided with curved ends 8, and a buckle-loop 9 has its opposite ends pivotally mounted in openings formed in said curved ends of the said prong-bar 6. The bars 4 and 6 are what may be termed "fixed" cross-bars.

The operation is as follows: The front end of the shoulder-strap 1 is passed downwardly through the openings 5 of the buckle 3 in front of the cross-bars 4 and 6, and is then passed downwardly through the bottom strap-loop 10, and is then passed upwardly and inserted through the buckle-loop 9 and thereafter made to engage the prongs 7, as shown in Figs. 1 and 2. The said shoulder-strap will thereby be securely held in position described and no further adjustment will be necessary until the shoulder-straps stretch in use. When it is desired to shorten the shoulder-straps, 70 all that is necessary for the wearer to do is to pull the strap farther through the main suspender-buckle and then take hold of the projecting end 11 of the shoulder-strap and pull the strap through the buckle-loop 9 a sufficient distance, after which the surplus may be cut off and thrown away, and this operation may be continued any number of times, depending upon the pleasure of the wearer, and in all cases the suspender-buckle 3 will remain 80 substantially in its original position—in other words, the said buckle 3 will not have to be placed nearer the wearer's shoulders each time an adjustment takes place.

I do not limit myself to the exact construction of the old parts of the buckle 3, as any other common buckle may be fitted with my invention.

What I claim is—

1. A suspender-buckle constructed with the usual strap-openings for permitting the shoulder-strap to slip through it, and also provided with a fixed cross-bar carrying prongs, and a pivoted loop to coöperate with said prongs; substantially as specified.
2. A suspender-buckle having a fixed cross-bar and strap-openings, downwardly-projecting prongs on the cross-bar adjacent to said openings and a loop pivotally mounted at its ends to coöperate with said prongs in holding a strap.
3. A suspender-buckle having strap-open-

ings separated by a fixed cross-bar, an additional fixed cross-bar extending parallel to the first-mentioned cross-bar, prongs projecting downwardly from said additional cross-bar, 5 and a loop pivotally connected to said additional cross-bar; substantially as specified.

In testimony whereof I have signed my name

to this specification in presence of two subscribing witnesses.

HENRY R. WEBB.
